UNITED STATES PATENT OFFICE.

FREDERICK W. GRIMES, OF MAPLEWOOD, NEW JERSEY, ASSIGNOR OF ONE-HALF TO
LA MONT RALSTON, OF NEW YORK, N. Y.

FLOOR MAT.

Application filed November 15, 1923. Serial No. 674,838.

To all whom it may concern:

Be it known that I, FREDERICK W. GRIMES, a citizen of the United States, and resident of Maplewood, in the county of Essex and State of New Jersey, have invented certain new and useful Improvements in Floor Mats, of which the following is a specification.

Mats or runners for floors have been made comprising plates or layers of suitable material, such as leather, strung on wires, and in some forms of such mats or runners the plates of leather have been arranged in series side by side to constitute units or links, which units have been attached together by wires with the units arranged alternately, somewhat in the nature of chains, whereby the mats or runners are flexible and foldable. The leather used in the units or links is liable to swell when wet and thereby to bend or distort the wires connected with the units or links, which wires remain bent or distorted even though the leather shrinks when dry, and end portions of such mats have been relatively weak so as to be injured when struck by the shoes of persons walking on the mats. Furthermore, such leather links are liable to stain floors when the leather becomes wet.

One of the objects of my invention is to provide a mat or runner of the class referred to in which units or links are made of rigid material which will be strong and durable. A further object of my invention is to make the end or edge portions of the mat or runner strong and durable to resist blows from shoes, and to provide that two adjacent end sections will be united together in such a way as to be folded as a unit when the mat is folded, irrespective of the way in which the other portions of the mat may be folded together.

My invention comprises novel details of improvement that will be more fully hereinafter set forth and pointed out in the claims.

Reference is to be had to the accompanying drawings forming a part hereof, wherein

Fig. 1 is a plan view illustrating my improved mat;

Fig. 2 is an edge view of Fig. 1;

Fig. 3 is a perspective view of one of the rubber units or links;

Fig. 4 is a perspective of one of the marginal units or links of the mat;

Fig. 5 is a similar view of one of the units or links at the ends of the mat that connect an end section portion to an adjacent portion;

Fig. 6 is a perspective view showing a frame for connecting the units, and

Fig. 7 is a detail of a bushing for the units.

Similar numerals of reference indicate corresponding parts in the several views.

The main units or links 1, 2 of the mat are arranged in parallel rows, preferably extending end to end lengthwise of the mat, the units of one row alternating with units of adjacent rows, except the end rows of the mat, which units or links are pivotally connected by means of frames 3 comprising parallel rods or pins 3' that pass through holes in the units or links adjacent to their ends. In the example illustrated the rods or pins 3' are connected at adjacent ends by means of cross bar 3^a, the frame being substantially in U-form, whereby the ends of alternate links are connected with the rods in an ordinary way. The free ends 3^b of the frame 3 are shown bent sideways over the outer surfaces of adjacent units and retained by sleeves 4 as well known. Apertured plates 6 are shown located between cross bars 3^a, bent ends 3^b and the outermost adjacent units. The links 1 in the example illustrated are solid, whereas the links 2 are shown comprising layers of material placed side by side, such as of leather. Hollow rivets or bushings 5 pass through the units and the ends are riveted over the corresponding sides of the units, which hollow rivets provide metal bearings for the rods or wires 3 and serve to retain together the layers of the units 2, as well as to strengthen and stiffen the material of the units. The outer surfaces of the units may be flat or may be curved or corrugated, or may have any other suitable shape. The solid units 1 or links 1 are composed of rubber or a suitable rubber composition, so as to be strong, solid and rigid and of a character not to stain floors when wet. The units 2 or any of them may be similar to the units 1. I have illustrated the units 2 as comprising several layers of material, such as leather, which in a mat of relatively large dimen-

sions would not be objectionable when the main quantity of the units or links¹ of the mat are made of rubber, it being understood further that the layers of the units or links 5 2 may be made of rubber if desired.

It will be noted that there are spaces between the ends of the units 1 and the units 10 2 in the corresponding rows of units, which spaces are provided by reason of the alternating arrangement of the units, and in the example illustrated the two units of alternating rows of units at the ends of the mat are close together or abut at their ends, which is accomplished by locating the adjacent 15 rods or wires of the endmost connecting frames 3 sufficiently close together to cause the abutting of the aforesaid units, because there are no units interposed between said wires to spread them apart. The units 1^a, 20 which may comprise layers of leather or other suitable material, or may be solid and of rubber as described respecting units 1, are relatively long to not only receive the outermost frames 3 of the end portions of the mat 25 but to receive the adjacent wire of the next adjoining frame 3, at the corresponding end of the mat, the units 1^a being shown provided with holes having bushings 5 to receive the wires of the first named frames and 30 other holes 5^a having bushings 5 to receive the adjacent wires of the second named frames. The units 1^a are shown between units 2 strung along the corresponding connecting frames 3 at the ends of the mat. 35 The inner ends of the units 1^a are thus spaced from the opposing ends of the next units 1 of the same row of units, and the inner ends of the units 1^a are between the abutting units of alternate rows of units on 40 opposite sides thereof.

In order to connect together the two adjacent transverse series of units 1^b, 1^c at the ends of the mat, I provide connecting members 7 which have spaced pairs of openings 7^a, each pair being adapted to receive the rods 3' of the corresponding frame 3, whereby said adjoining frames are maintained in relative position and will rotate or fold as a unit pivoted upon the next transverse series of units 1. The arrangement described is such that the aforesaid 45 two transverse series of units 1^b, 1^c, at the end portions of the mat, are always main-

tained in a relative position to rest smoothly upon the floor, and the members 7 also serve 55 to aid in preventing bending or distortion of the corresponding frames 3.

In accordance with my improvements the mat is adapted to lie flat upon the floor and the end portions will remain flat and smooth 60 without danger of bending upwardly, the two endmost transverse series of units 1^b, 1^c that are connected by the members 7 resisting tendency to cause them to be swung upwardly or bent when encountered by the 65 shoes of pedestrians. By having the inner ends of units of the endmost series 1^b abutting the opposing ends of the next units in the same row in the series 1^c blows against the outer edges of the endmost series are transmitted to the said units of series 1^c and the ends of the mat are greatly strengthened and wear at the ends of the mat is reduced. When the mat is to be folded the said connected end-units 1^b, 1^c will rotate together 70 upon innermost rods 3' of inner frames 3, the remainder of the units being folded as may be desired so that the endmost units 75 always remain firmly united together.

Having now described my invention, what so I claim is:

1. A mat of the character described comprising a plurality of parallel rows of units, and frames comprising spaced bars connecting said units together, the adjacent ends 25 of units of some rows at the ends of the mat abutting end to end, and units in other rows, between the last named units receiving a plurality of bars of one frame and one bar of the adjoining frame at the corresponding end of the mat.

2. A mat of the character described comprising parallel rows of units, frames connecting the units, and members separate from the frames independent of the units 95 and located between adjacent rows of units connecting together adjoining frames at the ends of the mat in a non-flexible section including two transverse rows of units.

3. A mat of the character described comprising parallel rows of units, frames connecting the units, and members provided with pairs of spaced openings, each pair of openings receiving the adjoining frames at the ends of the mat.

FREDERICK W. GRIMES.
